UNITED STATES PATENT OFFICE.

JOSEPH W. KRAUSE, OF BROOKLYN, NEW YORK.

BRASSIÈRE.

Application filed April 11, 1927. Serial No. 182,589.

This invention relates to brassières and aims to improve the construction and appearance of these articles of apparel.

An object of the invention is to provide a brassière that will at all times be maintained in close contact with the bust and will not fall outwardly when the wearer bends over as is usual with brassières now in common use.

10 The invention also provides a brassière that is maintained in proper position without the aid of shoulder straps and hence provides a more sightly article of apparel than the ordinary brassière, and one that is particularly adapted for use with evening gowns or with other costumes in which shoulder straps are objectionable.

Preferred forms of the invention are set forth herein, but it should be understood 20 that various changes may be made in the structure without departing from the spirit and scope of the invention as hereinafter set forth and claimed.

In the drawings:

25 Fig. 1 is a front perspective view showing the brassière in use.

Fig. 2 is a rear perspective corresponding to Fig. 1.

Fig. 3 is a perspective view showing the 30 wearer in a bending position.

Fig. 3a is perspective of the brassière in use in Fig. 1, with slight modifications of structure.

Fig. 4 is a plan view of the front of the 35 brassière.

Fig. 5 is a plan view of the back of the brassière.

Fig. 6 is an enlarged view showing details of construction.

40 Fig. 7 is a plan view of the front of a modification.

Fig. 8 is a perspective of the rear of the article of Fig. 7.

Fig. 9 is a rear perspective showing the 45 article of Fig. 7 in use.

The simplest form of the invention is shown in Figs. 7 to 9, which disclose a brassière made up of a central section 10, intermediate sections 11 and end sections 12.

50 These sections are disposed vertically and joined together as by suitable stitching, the sections being so shaped that the completed brassière will conform to the figure of the wearer. The lower edge of the brassière is bound with tape as at 13 and a decorated

finishing strip 14 is secured along the upper edge. Suitable fastening devices 15 are mounted on one of the end sections 12 and the other end section carries a piece of elastic 16 which has fasteners 17 for cooperation 60 with the fasteners 15. A garter supporting tab 18 is attached to the lower end of the central section 10.

The brassière is worn in the manner indicated in Fig. 9 with the elastic passing 65 around the back of the wearer and holding the front part of the brassière firmly against the body.

For certain uses, such as in connection with very thin gowns, it is desirable to conceal the elastic 16 and to have the brassière 70 form a more continuous undergarment around the back of the wearer. In this case a brassière of the type illustrated in Figs. 1-6 would be advisable. The main supporting part of this garment is substantially 75 the same as that already described, but in addition there are provided back-covering sections that extend over the elastic 16 when the garment is worn.

80 This brassière is formed of a central section 19, intermediate sections 20, and end sections 21 and 22. These sections are of such size and shape that when joined together they form a garment completely encircling the body as indicated in Figs. 1-3. Small attaching ends 23 and 24, similar to the end sections 12 of Fig. 7 are secured to the inner side of the brassière at the seams between sections 21 and 22 and the intermediate sections 20, the end 23 carrying the elastic 25 while the end 24 has fasteners 26 for cooperation with the fasteners 27 of the elastic. A row of tape 28 is secured to the inner side of the garment extending 90 from the upper part of the end 24 diagonally across the top of section 20 to the upper edge of section 19. In like manner a tape 29 extends diagonally across the lower end of section 20, and other similar tapes 100 connect the section 23 with the ends of section 20. These diagonal tapes carry the pull of the elastic directly to the top and bottom edges of the middle section 19 and serve to hold these sections in toward the 105 body.

110 Triangular elastic sections 30 are inserted between the sections 21 and 22 and the intermediate sections 20 in order to form yielding portions over the hips of the wearer and

permit the garment to accommodate itself to bending movements of her body.

Fig. 2 clearly shows how the elastic fastens around the back before the end sections 5 21 and 22 are hooked together, and Fig. 3 illustrates the manner in which these ends 21 and 22 conceal the elastic and cooperate with the front sections to completely encircle the body.

10 It will be apparent that the elastic section around the back holds the brassière firmly against the front part of the wearer's body so that no shoulder straps are needed. This snug resilient fit of the brassière supports the weight of the breasts and keeps the brassière from falling away from the body when the wearer bends forward as in Fig. 3.

15 In the modification shown in Fig. 3^a the rear section 32 extends entirely around the back of the wearer and is fastened to the side of the body along the edge 33. An elastic 31 is fastened within the rear section 32 and is of smaller size than the rear sec-

tion so that it acts in the same manner as the 25 elastic sections 16 and 25.

I claim:—

A brassière having a central front section, a pair of front side sections on opposite sides of the front section, a pair of rear sections each attached to the rear edge of a respective side section, reinforcing tapes at the lines of junction of the rear and side sections, a pair of diagonal reinforcing tapes 30 on each side section respectively extending downwardly from the upper corner and upwardly from the lower corner of the adjacent side of the center section and terminating at the first mentioned tapes, tabs 35 secured to the body of the garment on the inner side thereof at the junctions of the diagonal and first mentioned tapes, waist belt members extending from said tabs, means to connect the free edges of the back members, and means to connect said waist 40 belt members.

In testimony whereof I affix my signature.
JOSEPH W. KRAUSE.
